UNITED STATES PATENT OFFICE

2,551,191

SEPARABLE HINGE CONSTRUCTION

Christian R. Wartenberg, Chicago, Ill.

Application February 3, 1948, Serial No. 6,042

1 Claim. (Cl. 16—172)

1

This invention relates to an improvement in a separable hinge hanger construction. More particularly, this invention relates to a novel separable hinge bracket of the type utilized for retaining a sash or a screen frame in a window frame construction.

The hanging of window screening or storm sash has always presented a difficult problem with conventional types of hanger constructions. Where the windows are all located on the ground floor of a house the problem is not as acute as it is when the windows are located on upper floors of such an establishment.

In the hanging of storm sash above the ground floor, it is desirable to hang the same from the inside of the house, since most individuals are not amenable to the utilization of ladders and the attendant difficulties and dangers which may readily be encountered. In order to permit the hanging of a storm sash from the inside, there has developed a conventional separable type hook and plate construction. Essentially this design embodied a pair of hooks which were attached to the upper portion of a window frame. A pair of flat plate members, with rectangular apertures, were in turn attached to the sash frame and were adapted to engage the hooks in hanging relation, thereby maintaining the sash in place. This type of design permitted the hanging of the sash from the inside of a house but did not eliminate all of the dangers present in the operation. It did, in fact, establish new difficulties. With this type of hanger, the individual is unable to see the hooks since they are fastened above the window frame. Therefore, to properly hang the sash, the individual must first lean out of the window and determine the location of the hooks. He then must tilt the sash angularly out of the frame a considerable distance, thus necessitating bodily leaning outwardly. Realizing that in many instances the sash is quite heavy, it can readily be appreciated that the individual is in an extremely hazardous position, where loss of balance might easily cause bodily injury. With this conventional type of construction applicant has himself experienced many difficulties, since in many instances the hooks and plates will become readily bent or deformed, which will thus make the task increasingly more difficult. It is applicant's prime objective, therefore, to provide an improved separable hinge hanger design for window constructions that will efficiently and inexpensively solve the problems and dangers above mentioned.

Another object is to provide a hinge hanger construction including a bracket adapted to be

2

connected to the side members of a window frame, and a hinge member connected to a storm sash and adapted to separably and hingedly engage the bracket.

5 Another object is to provide a hinge hanger for a sash and window construction, said construction including a pair of brackets mounted on the sides of the window frame, clearly in view of an individual replacing the sash, and a pair of hinge members connected to the sides of the window and projecting outwardly therefrom for engagement with the brackets.

A still further object is to provide a separable hinge hanger for storm sash, said hinge hanger 15 including an improved design whereby the sash may readily be removed and replaced by hingedly swinging the sash outwardly but a minimum distance, and without the necessity of lifting the sash upwardly during removal of the same.

20 A still further object is to provide a hanger bracket for a sash and window construction, said bracket including upward sloping surfaces arranged to facilitate the installation of the sash and adapted to engage hinge members for locking 25 said sash within the window frame.

These and other objects will become more readily apparent from a reading of the specification when examined in conjunction with the accompanying drawing.

30 In the drawing:

Figure 1 is a front view of a storm sash and window frame construction showing a pair of separable hinge hanger brackets.

Figure 2 is an enlarged front view of a corner 35 of a sash and window construction showing the separable hinge hanger brackets.

Figure 3 is a sectional view taken along the line 3—3 of Figure 2.

Figure 4 is a detail side view of a hanger 40 bracket.

Figure 5 is a front view of the same.

Figure 6 is a plan view of the same.

Figure 7 is a detail front view of a hinge 45 member.

Figure 8 is a detail end view of the same.

Referring generally to Figure 1, a standard type window frame is designated by the numeral 10. The frame 10 includes top and bottom frame members 11 and 12, respectively, and side members 13. A parting strip 14 is provided around the inner surfaces of the frame members in a conventional manner. A removable sash 15 is mounted within the frame 10. This sash is of a standard type used during the winter months and may generally be designated as "storm sash."

Referring particularly to Figures 4, 5, and 6, a hanger bracket is designated by the reference character 20. The bracket 20 includes a flat plate 21 having a plurality of holes 22. For the purpose of disclosure, the bracket 20 is shown as being of stamped sheet metal construction but it can, of course, be made of a casting material or other metal. An arm 23 projects outwardly from the flat plate 21. The arm 23 is provided with a substantially wide flat upwardly sloping surface 24. The surface 24 is tangent to a curved edge portion 25, which forms a hinging surface, as will presently be described. The curved edge portion 25 is formed as a part of a circle and has one portion tangent with the flat plate 21. The center line of the circle forming the curved edge portion is below the upper edge of the plate 21, as best shown in Figure 4.

The bracket also includes a sliding surface 26 which extends upwardly at a greater angle than the surface 24. This surface terminates above the upper edge of the flat plate 21. The sliding surfaces 24 and 26 are reinforced by a web 27.

A hinge bracket is shown in Figures 7 and 8 as indicated by the reference character 30. The hinge bracket includes a flat plate portion 31 and an angular portion 32 extending outwardly therefrom. A hinge pin 33 is formed at the end of the angular plate portion 32 and this hinge pin extends laterally outwardly with respect to the plate 31.

As best shown in Figures 2 and 3, the bracket 20 is connected to the side frames 13 of the window frame by screws 35. The center line A of the center of the hinging surface formed by the curved edge portion 25 is substantially in the same horizontal plane as the top surface of the sash 15. Thus the hinge line is level with the top surface of the sash. The hinge brackets 30 are connected to the upper frame members of the sash 15 by screws 36. They are so positioned that the center of the hinge pin 33 is also level with the top surface of the sash and coincident with the center line A.

In assembling the sash within the window frame, the person assembling the same merely stands inside the house and lifts the top of the sash vertically above the brackets 20. The surface 26 forms both a sliding surface and a hook portion. The hinge pins 33 project laterally outwardly from the sides of the sash, and he hooks the hinge pins over the surface 26 in the manner shown by the broken line position B of Figure 3. The hinge pins 33 slide down the surface 26 to the position shown by C in broken lines. Thereupon the assembler slightly tilts the sash outwardly and the hinge pins thereupon ride in the curved edge portion 25, or hinging surface. He then pulls the sash inwardly into place.

The sash is now rigidly secured in place and can be opened by merely tilting the sash, which is now riding or hinging in the curved edge portion 25. The portion of the plate 21 above the curved edge portion acts as a bearing member for the hinge pin 33. The upwardly sloping surface 24 serves as a cam to keep the sash in place. As best shown in Figure 3, any outward thrust on the sash is immediately restrained by the upwardly sloping surface which reacts on the hinge

pin 33. Thus a positive lock is provided. In order to remove the sash, all one is required to do is to tilt the sash outwardly at a slight angle and then glide or slide the same outwardly on the surfaces 24 and 26. The individual is not required to lift upwardly on the sash in order to unhook the same in the manner of conventional hanger constructions.

The unique simplicity and novelty of the construction should now be clearly apparent. The hanger bracket and hinge form an inexpensive positive construction. The bracket and hinge members are so positioned that the assembler can see them when he is replacing the sash.

By placing the center line of the hinge even with the top surface of the sash, and by sloping the surface 24 upwardly, a camming action results which serves to provide a positive means for keeping the sash in place.

It is to be understood that applicant has shown a complete embodiment of his invention but that changes may be made which do not depart from the spirit of the invention as shown, nor the scope thereof, as defined in the appended claim.

What is claimed is:

A separable hinge-hanger construction for locking and removably supporting a sash within a window frame comprising in combination; a hinge bracket including a vertical plate member, a supporting arm extending outwardly from the plate member, said supporting arm having a curved hinging surface adjacent the plate member, a sliding surface on said arm, said surface extending upwardly in a slight angular incline with respect to said plate member and being tangential to the curved hinging surface, the sliding surface extending a distance outwardly from the plate member, said distance being greater than the cross sectional thickness of the sash, and a hinge member including a base and a circular hinge pin projecting laterally outwardly from the base; the hinge member being adapted to connect to the sides of a window frame adjacent the top edge of a sash with an axial centerline through the hinge pin being approximately at the same vertical level as the top edge of the sash, the hinge pin extending laterally outwardly from the side of the sash and engaging the sliding surface of the arm whereby said surface provides a restraining action to maintain the sash in the frame in the installed position against direct outward pressure on the sash, and whereby upon the sash and hinge pin being hingedly pivoted on the hinge bracket, the sash may be slidably moved on the sliding surface free of the window frame.
